2 SHEETS—SHEET 2.

UNITED STATES PATENT OFFICE.

ELLIS J. G. PHILLIPS, OF AURORA, ILLINOIS, ASSIGNOR TO RICHARDS-WILCOX MANUFACTURING COMPANY, OF AURORA, ILLINOIS, A CORPORATION OF ILLINOIS.

FIRE-DOOR.

1,395,766.

Specification of Letters Patent.

Patented Nov. 1, 1921.

Application filed May 17, 1920. Serial No. 382,010.

To all whom it may concern:

Be it known that I, ELLIS J. G. PHILLIPS, a citizen of the United States, and a resident of Aurora, in the county of Kane and State 5 of Illinois, have invented certain new and useful Improvements in Fire-Doors, of which the following is a specification, reference being had to the accompanying drawings.

10 My invention relates to fire doors of the type having its body formed of two sheet metal plates spaced apart and preferably having a sheet of refractory material such as asbestos interposed between the plates. It 15 is the object of my invention to provide a new and improved form and arrangement of parts by which the required stiffness is given to the door as a whole while at the same time providing for the expansion of the 20 parts under the influence of intense heat without danger of having the door twisted or warped out of shape. The preferred means by which I have accomplished my 25 object are illustrated in the drawings and are hereinafter specifically described. That which I believe to be new and desire to cover by this application is set forth in the claims.

In the drawings,—

30 Figure 1 is a front face view of my improved door supported in position to close a door opening;

Fig. 2 is an enlarged detail, partly broken away, being a horizontal section taken on 35 line 2—2 of Fig. 1;

Fig. 3 is a perspective view of the back face of my improved door, one side of the door being removed for showing a vertical section of the door;

40 Fig. 4 is an edge view of the upper portion of the door as seen from the left in Fig. 3; and

Fig. 5 is an edge view of the lower end portion of the door also as seen from the left 45 in Fig. 3.

Referring to the several figures of the drawings in which corresponding parts are indicated by the same reference characters,—

50 10 indicates the front plate of my door, 11 the rear plate, and 12 a sheet of asbestos interposed between said two plates. A series of rivets 13 adjacent to the upper, lower

and both side edges of the door serve to secure the plates 10 and 11 and the asbestos 55 sheet 12 in fixed position with respect to each other. One of the plates, which, in the construction shown is the front plate 10, is provided with vertical corrugations therein, while the other plate is provided with horizontal corrugations, whereby the expansion 60 of either plate longitudinally of the corrugations therein is readily taken care of in the other plate.

As is best shown in Fig. 2, stiffening 65 members are provided at each side of the door. The stiffening member at each side is in the form of a heavy angle iron 14 which is secured as hereinafter described to the front plate 10, and a lighter angle bar 15 70 which is secured as hereinafter described to the back plate 11. Two of the flanges of the angle bars 14 and 15 are in contact, and the other flanges are in spaced parallel position. As is clearly shown in said Fig. 75 2, the front plate 10 is turned about the angle iron 14 and about the rear edge of the angle bar 15, rivets 16 and 17 being inserted through the parts and serving to hold the angle bars rigidly in position with respect 80 to each other and also serving to hold the turned edge of the front plate 10 in position. The openings through the angle bars 14 and 15 through which the rivets 16 and 17 pass are in the form of slots in the upper 85 ends of which the rivets are adapted to stand normally, see Fig. 3. Bolts 18 extend through suitable openings in the plates 10 and 11, the sheet 12, and the angle bars 90 14 and 15 for securing such parts in position. The openings through the angle bars 15 for the bolts 18 are, with the exception of the openings for the uppermost bolts at each side of the door, in the form of horizontally-disposed slots whereby upon the expansion of the plate 11 longitudinally of the corrugations therein the bolts 18 are adapted 95 to yield laterally so as to prevent distortion of the door. As will be noted in Fig. 2, the edges of the plate 11 are spaced away 100 from the angle irons 14 so as to allow for an expansion of such plate laterally.

As is best shown in Fig. 1, hinge bars 19 and 20 extending across the front face of the front plate 10 are secured to the door 105 by means of bolts 21 and 21^a near the side

edges of the door, said bolts each passing through the front plate 10, an angle bar 14, insulating sheet 12, back plate 11 and an angle bar 15,—the bolts 21 at one side of 5 the door passing through horizontal slots and, as shown, the bolts 21^a passing through slots in the hinge bars. The hinge bars 19 and 20 are provided with suitable eyes upon their outer ends which are adapted to be 10 supported by pivot pins 22 mounted upon the frame of the door.

Stiffening means is provided also at the top of the door. As is shown in Fig. 3, this stiffening means comprises a heavy bar 23 15 which is held in position by an angle bar 24 and a sheet metal cover plate 25. The angle bar 24 has its horizontally-disposed flange in contact with the rear portion of the under face of the bar 23, and the cover 20 plate 25 is folded about the rear edges of the plate 23 and the horizontal flange of the angle bar 24, being held in position by means of rivets 26. At the front edge the cover plate 25 is turned downward upon 25 the outer face of the front plate 10 into position parallel with the vertical flange of the angle bar 24. At the sides of the door the uppermost bolts 18 that have been heretofore referred to serve to hold the cover 30 plate 25, the plates 10 and 11, the asbestos sheet 12, and the angle bar 24 in position, and also serve to connect such parts with the laterally-disposed flanges of the vertical angle bars 15. The openings for the uppermost bolts 18 in the angle bars 15 are in 35 the form of vertical slots so as to permit an expansion of the angle bars 15 without causing a distortion of the structure at the top of the door. Other bolts 27 are provided for securing the cover plate 25, the angle bar 24, and the body portion of the door rigidly together. The cover plate 25 is provided at each of its ends with flaps 28 and 29 formed integrally with the vertically-disposed portion and the horizontal portion respectively, such flaps being folded 45 about one of the edge portions of the door where they are held in position by the rivets 16 and 17, one of such corner constructions being shown in Fig. 4.

The stiffening structure at the bottom of the door comprises a heavy bar 30 in contact with a flange 31 formed integrally with the back plate 11. A cover plate 32 is 55 turned about the rear edges of the flange 31 and the bar 30 where it is held in position by a series of rivets 33, the openings for the rivets 33 being in the form of slots in the bar 30, as shown by dotted lines in 60 Fig. 2. At the front the cover plate 32 is turned back a short distance about the bar 30 and is then turned upward between the plates 10 and 11 to lie alongside and against the asbestos sheet 12. The lowermost bolts 65 18 at the sides serve to hold the plates 10

and 11, the asbestos sheet 12, the upwardly turned portion of the cover plate 32, and the laterally-disposed flanges of the angle bars 14 and 15 in position with respect to each other. Other bolts 34 are provided intermediate the sides of the door for connecting the upwardly turned portion of the cover plate 32 with the body portion of the door. The bottom cover plate 32 at each of its ends is provided with a flap 75 35 formed integrally with the horizontally-disposed bottom portion thereof, which flap is turned up and lies against the outer face of the adjacent angle iron 14 and is secured in place by two of the rivets 16 and 17, 80 as is best shown in Fig. 5.

While I have shown each of the plates 10 and 11 as being formed in a single piece, it will be understood that I do not wish to be restricted to this construction, inasmuch as either one of the plates may, without departing from my invention, be formed either integrally or of a plurality of sections suitably secured together.

What I claim as my invention and desire to secure by Letters Patent, is—

1. A door comprising two sheet metal plates spaced apart forming the body of the door, two angle bars secured to each of the side portions of said plates respectively, and means securing said angle bars together.

2. A door comprising two sheet metal plates spaced apart and forming the body of the door, and two angle-iron members 100 at each side portion of the door, one of said plates being secured to one of said angle-iron members and the other plate being secured to both of said members.

3. A door comprising in combination two 105 sheet metal plates forming the body of the door, two angle-iron members at each side edge of the door, one of the flanges of each of said angle-iron members standing at right angles to the faces of the door, said two 110 flanges being in contact with each other, and the remaining flanges being substantially parallel with the faces of the door and spaced apart from each other, and means securing said body portion and angle-iron members together.

4. A door comprising in combination two sheet metal plates spaced apart and forming the body of the door, two angle-iron members at each side edge of the door, one of the flanges of each of said angle-iron members standing at right angles to the faces of the door, said two flanges being in contact with each other, and the remaining flanges being substantially parallel with the faces of the door and spaced apart from each other, securing means passing through both of said spaced-apart flanges and through both of said spaced-apart plates, and other securing means passing through 130

both of the said contacting flanges and through a turned portion of one of said plates.

5. A door comprising two sheet metal plates, a sheet of refractory material interposed between said sheet metal plates, a heavy angle iron secured to the edge portion of one of said plates, and a light angle bar extending in the same direction and secured to said angle iron and to the edge portion of the other plate.

6. A door comprising two sheet metal plates spaced apart forming the body of the door, an angle bar secured to the upper marginal portion of one of said plates, a sheet metal cover plate extending about the horizontal flange of said angle bar and folded down on the outer face of the other of said two plates, and bolts passing through the vertical flange of said angle bar, through the upper marginal portions of said plates, and through the turned-down edge of the cover plate.

7. A door comprising two sheet metal plates spaced apart forming the body of the door, an angle bar extending along the upper edge of one of said plates, a heavy bar in horizontal position on top of said angle bar, a sheet metal cover plate extending about the horizontal flange of said angle bar and said heavy bar and folded down on the outer face of the other of said two plates, means for securing together said heavy bar, said angle bar and said cover plate, and bolts passing through the vertical flange of said angle bar, through the upper marginal portions of said plates, and through the turned-down edge of the cover plate.

40 8. A door comprising two sheet metal plates spaced apart forming the body of the door, a stiffening bar secured along the side of the door, a stiffening bar secured along the top of the door, a sheet metal cover plate extending about the top stiffening bar and folded down on the outer face of one of said plates, a flap formed with the turned-down portion of the cover plate, a second flap formed with the horizontal top portion of

50 the cover plate, one of said flaps being turned to lie against the edge of the door

and the other flap lying against the first-turned flap, and means securing said flaps to the side stiffening bar.

9. A door comprising two sheet metal plates spaced apart forming the body of the door, a heavy bar below a horizontal flange turned on the lower edge of one of said plates, a sheet metal cover plate extending substantially about said bar and about the outer edge of said flange and extending upward between said first-named two plates, means securing together said cover plate, said heavy bar and said flange, and means securing together the turned-up edge of said cover plate and said first-named two plates.

10. A door comprising two sheet metal plates spaced apart forming the body of the door, angle bars secured to said plates respectively along one edge of the door, the edge portion of one of said plates being turned about the side flange of the angle bar to which it is secured and about the edges of the side flanges of both of said angle bars, and fastening devices passing through the turned portion of the plate and through longitudinally-disposed slots in said angle bars for securing said parts together.

11. A door comprising a sheet metal plate having transversely-extending corrugations therein, a second sheet metal plate having vertical corrugations therein, said two plates forming the body of the door, angle bars extending along the side of the door and arranged with their laterally-disposed flanges adjacent to said plates respectively and with their side flanges adjacent to each other, bolts securing said laterally-disposed flanges to said plates, the openings in the first-named plate for said bolts being in the form of laterally-disposed slots, the edge portion of said second plate being turned about the side flange of the angle bar adjacent thereto and about the edges of the side flanges of both of said angle bars, and rivets passing through the turned portion of the second plate and through vertically-disposed slots in said side flanges serving to secure said parts together.

ELLIS J. G. PHILLIPS.
